United States Patent Office

Des. 178,537
Patented Aug. 14, 1956

178,537

DISH OR SIMILAR ARTICLE OF HOLLOW WARE

David Rauch, Worcester, Mass., assignor to Van Brode Milling Co., Inc., Clinton, Mass., a corporation of Massachusetts

Application February 6, 1956, Serial No. 40,040

Term of patent 7 years

(Cl. D4—15)

Fig. 1

Fig. 2

Fig. 1 is a front elevation of a dish or similar article of hollow ware, showing my new design; and

Fig. 2 is a bottom plan view of the same.

I claim:

The ornamental design for a dish or similar article of hollow ware, as shown.
